UNITED STATES PATENT OFFICE.

SAMUEL NEWMAN, OF CINCINNATI, OHIO.

NECKTIE PRESSER.

Application filed September 29, 1924. Serial No. 740,562.

To all whom it may concern:

Be it known that I, SAMUEL NEWMAN, a citizen of the United States, residing at Cincinnati, in the county of Hamilton and State of Ohio, have invented certain new and useful Improvements in Necktie Pressers, of which the following is a specification.

My invention relates to garment pressing or stretching means, and its object is to provide a small, light, simple device in which a necktie may be held so as to eliminate the wrinkles which are caused by tying and wearing the necktie. Another object is to enable the user to insert the tie in the device readily and to stretch the tie firmly in correct position before applying the holding pressure. Other objects will appear in the course of the ensuing description.

I attain these objects by the device illustrated, for example, in the accompanying drawing, in which—

Figure 1 is a front view, and

Fig. 2 is a side view, the straight dotted lines indicating the position of the pressing plate before being closed on the tie, and in the operation of stretching the tie.

The body of the device is an elongated channel 1, which, instead of being flat, as in previous devices, is curved, with the channel opening radially outwardly of the curvature. At its upper end the channel 1 has an extension 2 with an aperture 3, by which the entire device may be hung up. In the adjacent end of this channel 1, extending across from one side 4 to the other, is a pin 5; and the pressing plate 6 extends under this pin and has its end formed into a roll surrounding the pin 5, forming a hinge 7 for the plate, on which it may be swung down into the channel 1, and which will hold this end of the plate while it is bent to the curvature of the channel 1. The lower end of the pressing plate 6 is curved forward, then backward, and then slightly forward for a short distance to form a finger-hold 8. The lower end of the channel 1 has its bottom extended past its sides 4 and bent backward and upward, forming a roll around the transversely inwardly extended hinge lugs 9 of the fastener 10 which is of bail-like formation with its middle part formed into a loop 11 by which it may be grasped and swung up on the hinge thus formed, to engage lateral transverse parts

12 in front of the most forwardly curved convex part 13 of the finger-hold 8. These parts are so proportioned that when the radial side parts 14 of the fastener 10 engage the ends of the sides 4 of the channel 1, the parts 12 have passed slightly above the most forward point of the convex part 14, pressing the plate 6 in and then allowing the plate to spring out slightly, after which the plate thus holds the fastener in closed position. The bottom of the channel 1 has a slot 15 close to the hinge 7 of the pressing plate; and preferably the channel 1 is wider at its lower end than at its upper end, with the plate 6 correspondingly shaped, with merely slight clearance between its edges and the sides 4 of the channel. Thus, the narrower upper part of the device is adapted to receive the narrower middle part of the necktie, with the wider parts of the tie nearer its end received in the wider lower part.

The necktie A (Fig. 2) is folded at about the point of the back of the neck and passed up through fastener 10, then the fold is slipped back through the slot 15 while the plate 6 is swung forward and upward away from the channel 1. The parts of the tie in front of the channel 1 are laid in the channel, and then the plate 6 is swung down and back so that its under side next to the lower edge of the channel slot 15 grips the necktie parts between itself and the channel edge. Then, while holding the plate 6 thus against the tie with one hand, which supports the device, the plate 6 is bent down and back into the channel with the other hand, which also is holding the tie stretched as the plate progressively presses the tie from the point of gripping to the lower end of the device. When the plate 6 thus is completely bent in around the curvature of the channel, the bail-like fastener 10 is swung up and secured against the convex part 13 of the finger-hold 8, holding the plate 6 tightly around the channel curvature with the stretched necktie between the plate 6 and the bottom of the channel 1. The device now may be hung up by the extension 2, and left until the tie again is to be used. The end parts b of the tie A hang down from the lower end of the device, only portions of these parts being illustrated, for lack of space. Thus, the necktie may be of any length; it is not necessary to press the end parts, as only the intermediate parts of the

tie become wrinkled, where the knot is made, nor is it necessary to press the part *c* that passes inside the collar and is not seen. Ties that have this part exposed around the collar, as with standing collars, do not have this part wrinkled in use. Thus, my device may be of moderate length, easily packed away, and not unwieldy, as are pressers made to take in the entire tie.

10 By having the channel curved, and the pressing plate straight when open, it is not necessary for the plate to be of highly resilient material, as where the plate is curved when open and the pressure is obtained by straightening the plate. This makes it possible to avoid the use of spring steel; and the device may readily be made chiefly of aluminum, the plate as well as the channel being of this metal, and therefore the device 15 may be very light as well as small and compact. With any material, its smallness, as well as its simplicity makes it very economical to manufacture.

Having fully described my invention, 20 what I claim as new and desire to secure by Letters Patent is:

1. In a necktie presser, a curved channeled body, the channel opening radially outward of the curvature, and a flexible pressing plate hinged between the sides of the channel 25 near one end and adapted to be bent around said curvature to the opposite end.
2. In a necktie presser, a curved channeled body, the channel opening radially outward 30 of the curvature, a flexible pressing plate

hinged between the sides of the channel near one end and adapted to be bent around said curvature to the opposite end, where said plate has a forwardly convex end part, and a fastener hinged in the sides of the channel near said opposite end and having a transverse part adapted to be swung in front of said convex part of the plate and held inwardly of said opposite end from the most prominent part of said plate convex part, 40 whereby the resilience of the plate retains the fastener in position to hold the plate bent around said channel as aforesaid.

3. A necktie presser comprising two members hinged together near one end, one of the members being rigid and curved, and the other member being flexible and substantially straight when the members are swung apart, and bent firmly around the curvature of the rigid member to hold a necktie against the rigid member.

4. A necktie presser comprising a channeled curved rigid member, and a flexible member hinged to the first member near one end thereof, to be bent around the curvature within the channel of said first member, and fastening means on said first member near its opposite end, engageable with the adjacent end of the second member when bent as aforesaid, the second member having a retentive part engaged by the fastener and being sufficiently resilient to retain said fastener while the fastener retains said second member in its bent condition.

SAMUEL NEWMAN.
